UNITED STATES PATENT OFFICE.

JOHN K. EDWARDS, OF PHILADELPHIA, PENNSYLVANIA.

INTERNAL-COMBUSTION ENGINE.

1,142,508.

Specification of Letters Patent. Patented June 8, 1915.

Application filed October 11, 1913. Serial No. 794,579.

To all whom it may concern:

Be it known that I, JOHN K. EDWARDS, of Philadelphia, in the State of Pennsylvania, have invented a certain new and useful Improvement in Internal-Combustion Engines, whereof the following is a specification, reference being had to the accompanying drawings.

My invention relates to engines wherein a single valve is operatively connected with the crank shaft to control both the inlet and exhaust valves, and, it is the object of my invention to provide simple and efficient means to positively operate such a valve.

As hereinafter described, my invention includes a hollow conical valve so constructed and arranged as to be maintained tight by the pressure in the engine cylinder, without the employment of packing or adjusting means, and, said valve is operatively connected with the crank shaft by Geneva stop gearing arranged to positively intermittently rotate said valve in proper time with respect to the movements of the piston.

My invention includes the various novel features of construction and arrangement hereinafter more definitely specified.

In the drawings:—Fig. I is a plan view of an engine embodying my invention. Fig. II is a vertical sectional view taken on the line II, II in Fig. I. Fig. III is a vertical sectional view taken on the line III, III in Fig. I. Fig. IV is a vertical sectional view taken on the line IV, IV in Fig. I. Fig. V is a vertical sectional view taken on the line V, V in Fig. I. Fig. VI is an inverted plan view of the cylinder head. Fig. VII is an inverted plan view of the rotary hollow conical valve.

In said figures; the cylinder 1 includes the water chamber 2 surrounding the piston chamber 3 provided with the piston 4. The cylinder head 5 has the water chamber 6 in communication with the water chamber 2 through the passageway 7 shown in Fig. III and has the conical valve seat 9 at the end of said cylinder with two diametrically opposed fuel inlet ports 10 and two diametrically opposed exhaust ports 12; said four ports being equidistantly spaced in the circumference of said seat 9 which is also provided with the ignition recess 14 in which extends the spark plug 15.

The hollow conical valve 18 is fitted to rotate in said valve seat and has the stem

19 extending through said head 5, conveniently provided with the oil passageway 20 by which said valve and its seat may be lubricated.

The crank shaft 22 is journaled in the bearings 23 in the engine base 24 and has its crank 25 operatively connected with said piston 4 by the pitman 26 engaging the pin 27 in said piston. Said crank shaft 22 has the beveled gear 30 at the outer end thereof engaging the bevel gear 31 on the counter shaft 32 which extends parallel with the axis of the engine cylinder and is journaled in the bearing 34 on said base 24 and in the bearing 35 on the cap 36 which covers the water chamber 6 in said head 5. Said counter shaft 32 has the intermittent gear wheel 38 extending above said head and having four teeth 41, 42, 43 and 44 on one-half of its periphery with cylindrical sectors 45 of uniform radius between them. The Geneva stop gear 48 on said stem 19 of the valve 18 has eight gear teeth recesses in its periphery fitted to the teeth on said intermittent gear 38 and has sectors 49 between said recesses curved to fit the sectors 45 on said intermittent gear; whereby said valve 18 is positively intermittently turned to open and close said inlet and exhaust ports and said ignition recess in proper relation with the movements of said piston 4; being prevented from turning otherwise by the engagement of said sectors 45 and 49.

The engine above described is adapted for four cycle operation, said crank shaft 22 making two revolutions for each revolution of the intermittent gear 38; and, the teeth 41, 42, 43 and 44 on said gear are so spaced that said valve 18 is turned to leave the fuel inlet ports 10 open while said crank shaft 22 turns one hundred and eighty degrees from the upper limit of its stroke, in the direction of the arrows marked thereon in Figs. II and III, then maintain said ports 10 closed during the succeeding movement of said crank shaft through one hundred and eighty degrees until the piston 4 reaches the upper limit of its stroke, and still maintain said ports 10 closed while the crank shaft turns from the upper limit of its stroke one hundred and eighty degrees under the impulse of the ignited gases, and, then open said exhaust ports 12 and maintain them open while said crank shaft 22 turns one hundred and eighty degrees. Whereupon, the tooth

42 engaging said gear 48 closes said exhaust ports, and, the tooth 43 also engaging said gear 48 thereupon opens said inlet valve 10 to the initial position shown in the drawings. 5 It may be observed that when said valve 18 is turned to close the inlet ports 10 one of the ports 21 in said valve registers with the ignition recess 14 so as to open the latter to permit the spark plug 15 to ignite the charge at the proper time. However, it is to be understood that my invention is applicable to engines which are not adapted for four cycle operation. Therefore, it is to be understood that I do not desire to limit myself to the 15 precise details of construction and arrangement herein set forth, as it is obvious that various modifications may be made therein without departing from the essential features of my invention as defined in the appended claims.

20 I claim:

1. In an internal combustion engine, the combination with a cylinder including a water chamber surrounding a combustion chamber provided with a piston; of a head having a water chamber in communication with the water chamber in said cylinder and a conical valve seat at the end of said cylinder with two diametrically opposed fuel inlet ports, and two diametrically opposed exhaust ports, opening therethrough, equidistantly spaced in the circumference of said seat; a spark plug extending in an ignition recess in said valve seat; a hollow conical valve fitted to rotate in said valve seat and having a stem extending through said head; a removable cap on said head, covering the water chamber therein and having a shaft bearing; a crank shaft; a pitman operatively connecting said crank shaft with said piston; a bevel gear on said crank shaft; a counter shaft extending parallel with the axis of said cylinder, in the bearing on said cap; a bevel gear on said counter shaft engaging the gear on said crank shaft; an intermittent gear on said counter shaft extending above said head, having four teeth on one half of its periphery with cylindrical sectors of uniform radius between them; a Geneva stop wheel on said valve stem having eight gear teeth recesses in its periphery fitted to the teeth on said intermittent gear, and having sectors between said recesses curved to fit the sectors on said intermittent gear; whereby said valve is positively intermittently turned to open and close said inlet and exhaust ports and said ignition recess in proper time with the movements of said piston and is prevented from turning otherwise, and is maintained tight by the pressure in said cylinder.

2. In an internal combustion engine, the combination with a cylinder including a combustion chamber provided with a piston; of a head having a conical valve seat at the

end of said cylinder with two diametrically opposed fuel inlet ports and two diametrically opposed exhaust ports opening therethrough, equidistantly spaced in the circumference of said seat; a spark plug extending in an ignition recess in said valve seat; a hollow conical valve fitted to rotate in said valve seat and having a stem extending through said head; a crank shaft; a pitman operatively connecting said crank shaft with said piston; a bevel gear on said crank shaft; a counter shaft extending parallel with the axis of said cylinder; a bevel gear on said counter shaft engaging the gear on said crank shaft; an intermittent gear on said counter shaft extending above said head, having four teeth on one half of its periphery with cylindrical sectors of uniform radius between them; a Geneva stop wheel on said valve stem having eight gear teeth recesses in its periphery fitted to the teeth on said intermittent gear, and having sectors between said recesses curved to fit the sectors on said intermittent gear; whereby said valve is positively intermittently turned to open and close said inlet and exhaust ports and said ignition recess in proper time with the movements of said piston and is prevented from turning otherwise, and is maintained tight by the pressure in said cylinder.

3. In an internal combustion engine, the combination with a cylinder including a combustion chamber provided with a piston; of a head having a conical valve seat at the end of said cylinder with two diametrically opposed fuel inlet ports and two diametrically opposed exhaust ports opening therethrough, equidistantly spaced in the circumference of said seat; a hollow conical valve fitted to rotate in said valve seat and having a stem extending through said head; a crank shaft; a pitman operatively connecting said crank shaft with said piston; a bevel gear on said crank shaft; a counter shaft extending parallel with the axis of said cylinder; a bevel gear on said counter shaft engaging the gear on said crank shaft; an intermittent gear on said counter shaft extending above said head, having four teeth on one half of its periphery with cylindrical sectors of uniform radius between them; a Geneva stop wheel on said valve stem having eight gear teeth recesses in its periphery fitted to the teeth on said intermittent gear, and having sectors between said recesses curved to fit the sectors on said intermittent gear; whereby said valve is positively intermittently turned to open and close said inlet and exhaust ports in proper time with the movements of said piston and is prevented from turning otherwise, and is maintained tight by the pressure in said cylinder.

4. In an internal combustion engine, the combination with a cylinder including a combustion chamber provided with a pis-

ton, and having a conical valve seat at the end of said cylinder with a fuel inlet port and an exhaust port opening therethrough; a hollow conical valve fitted to rotate in said 5 valve seat and having a stem; a crank shaft; a pitman operatively connecting said crank shaft with said piston; a bevel gear on said crank shaft; a counter shaft extending parallel with the axis of said cylinder; a bevel 10 gear on said counter shaft engaging the gear on said crank shaft; an intermittent gear on said counter shaft extending above said head, having four teeth on one half of its periphery with cylindrical sectors of uniform 15 radius between them; a Geneva stop wheel on said valve stem having eight gear teeth recesses in its periphery fitted to the teeth on said intermittent gear, and having sectors between said recesses curved to fit 20 the sectors on said intermittent gear; whereby said valve is positively intermittently turned to open and close said inlet and exhaust ports in proper time with the movements of said piston and is prevented from 25 turning otherwise, and is maintained tight by the pressure in said cylinder.

5. In an internal combustion engine, the combination with a cylinder including a combustion chamber provided with a piston, 30 and having a conical valve seat at the end of said cylinder with a fuel inlet port and an exhaust port opening therethrough; a hollow conical valve fitted to rotate in said valve seat and having a stem; a crank shaft; a pitman 35 operatively connecting said crank shaft with said piston; a bevel gear on said crank shaft; a counter shaft extending parallel with the axis of said cylinder; a bevel gear on said counter shaft engaging the gear on 40 said crank shaft; an intermittent gear on said counter shaft extending above said head, having teeth with cylindrical sectors of uniform radius between them; a Geneva stop wheel on said valve stem having teeth recesses in its periphery fitted to the teeth on 45 said intermittent gear, and having sectors between said recesses curved to fit the sectors on said intermittent gear; whereby said valve is positively intermittently turned to 50 open and close said inlet and exhaust ports and said ignition recess in proper time with the movements of said piston and is prevented from turning otherwise, and is main-

tained tight by the pressure in said cylinder.

6. In an internal combustion engine, the combination with a cylinder including a combustion chamber provided with a piston and having a conical valve seat with two diametrically opposed fuel inlet ports and 60 two diametrically opposed exhaust ports opening therethrough, equidistantly spaced in the circumference of said seat; a conical valve fitted to rotate in said valve seat, having two ports opening therethrough, equidistantly spaced in the circumference of said valve, and having a stem; a crank shaft operatively connected with said piston; means operatively connecting said crank shaft with said valve stem including Geneva 70 stop gearing arranged to maintain said inlet port open during one hundred and eighty degrees turning movement of said crank shaft and closed during the succeeding movement of said shaft through three hundred 75 and thirty degrees turning movement, and, maintain said exhaust valve open during the succeeding movement of said crank shaft through two hundred and ten degrees.

7. In an internal combustion engine, the combination with a cylinder including a combustion chamber provided with a piston and having a conical valve seat with a fuel inlet port and exhaust port opening therethrough; a conical valve fitted to rotate in 85 said valve seat and having a stem; a crank shaft operatively connected with said piston; means operatively connecting said crank shaft with said valve stem including Geneva 90 stop gearing arranged to maintain said inlet port open during one hundred and eighty degrees turning movement of said crank shaft and closed during the succeeding movement of said shaft through three hundred and thirty degrees turning movement, and, 95 maintain said exhaust valve open during the succeeding movement of said crank shaft through two hundred and ten degrees.

In testimony whereof, I have hereunto signed my name at Philadelphia, Pennsylvania, this tenth day of October, 1913.

JOHN K. EDWARDS.
